DESIGN FOR A JAR

Lysle E. Adams, Oak Park, Ill., assignor to Lysle E. Adams, as trustee

Application October 10, 1938, Serial No. 80,353

Term of patent 7 years

To all whom it may concern:

Be it known that I, Lysle E. Adams, a citizen of the United States, residing at Oak Park, in the county of Cook and State of Illinois, have invented a new, original, and ornamental Design for a Jar, of which the following is a specification, reference being made to the accompanying drawing forming a part thereof in which

Fig. 1 is a front elevational view of a jar embodying my new design;

Fig. 2 is a side elevational view of the same; and

Fig. 3 is a top plan view thereof.

I claim:

The ornamental design for a jar, as shown.

LYSLE E. ADAMS.
